UNITED STATES PATENT OFFICE

2,001,752

SECURING DEVICE

Frank E. Sinclair, Claremont, N. H., assignor to
 Sullivan Machinery Company, a corporation of
 Massachusetts

Application May 23, 1931, Serial No. 539,512

8 Claims. (Cl. 287—125)

This invention relates to securing devices, and more particularly to securing devices for locking together a plurality of relatively rotatable, threadedly connected parts.

5 An object of this invention is to provide an improved securing device. Another object is to provide an improved securing device for holding a plurality of relatively rotatable, threadedly connected parts together. A further object is to 10 provide an improved securing device in the form of a wedge coacting with a plurality of relatively rotatable, threadedly connected parts for locking the threaded joint therebetween against release. Yet another object is to provide an improved 15 securing device of the aforesaid character which comprises a wedge element disposable in a slot in one part and an annular groove in the other part, so that the wedge may be driven into the space formed by the slot and groove into its tightened position to lock the 20 threaded joint between the parts against loosening. These and other objects and advantages of this invention will, however, hereinafter more fully appear in the course of the following description and as more particularly pointed out in the appended claims.

In the accompanying drawing there is shown for purposes of illustration one form which the invention may assume in practice.

30 In this drawing,—

Fig. 1 is a side elevational view of a pneumatic pick of the percussive type having embodied therein the illustrative form of the improved securing device.

35 Fig. 2 is a longitudinal sectional view taken through the percussive motor shown in Fig. 1 and showing the securing device and its associated parts in detail.

Fig. 3 is a detail sectional view taken on line 40 3—3 of Fig. 2.

In this illustrative construction there is shown a pneumatic pick of the percussive type generally comprising a hammer motor 1 having a supporting handle 2 which carries a usual throttle valve 3 for controlling the supply of pressure fluid from a hose connection 4 through the handle 2 to the hammer motor 1 which is herein of the pressure fluid actuated reciprocating piston type. This hammer motor is adapted to actuate percussively a picking tool 5 held in position within the forward end of the hammer motor by a coiled spring retainer 6 of a well known design. In the present construction, the hammer motor 1 comprises a cylinder 7 having reciprocably mounted 50 therein a hammer piston 8 adapted to deliver a

series of impact blows to the shank of the picking tool 5, and the supply of pressure fluid to the motor cylinder is controlled by an automatic fluid distributing valve 9 of a well known design. The valve 9 is arranged within a valve chest 10 5 arranged within a detachable rear head member 11. The rear end of the motor cylinder is threadedly connected at 12 by right hand threads within the rear head 11, and the improved securing device is associated with the cylinder and rear head for maintaining the threaded joint 12, between the parts, tight. It will, however, be understood that the improved securing device may be incorporated in various other tools where 10 in a plurality of relatively rotatably threaded 15 parts are desired to be locked together.

The improved securing device, as mentioned above, is associated with the cylinder 7 and rear head 11 for maintaining the threaded joint 12 therebetween, when tightened, against loosening, 20 herein due to the vibrating action of the tool. This securing device herein comprises a slot 13 formed transversely in the head 11 and an annular groove 14 formed on the periphery of the cylinder 7, herein on that portion of the periphery of the cylinder which fits within a bore 15 formed in the head 11. Cooperating with the slot and groove and disposable in the space formed by the slot and groove is a wedge member 16 having a driving head 17 at one end. The 30 other end of the wedge is threaded at 18 to receive a tightening and holding nut 19. The wedge has its plane angle, i. e. the angle between its angularly extending wedging surfaces in a plane parallel to the axis of the threaded connection.

It will thus be seen that when the head 11 is tightly threaded onto the cylinder 7, the wedge 16 may be driven, by blows struck against the head 17 or by rotation of the nut 19, into the 40 space provided by the slot and groove, thereby to wedge the parts together and prevent loosening of the threaded joint 12 between the parts, and that irrespective of the relative angular positions of the head and cylinder, the threaded joint 45 may be held tight. The reason for this will be readily appreciated. The shoulder at the upper side of annular groove 14 engages the top surface of the wedge, while the lower surface of the wedge engages the shoulder at the lower side 50 of the slot 13. Rotation of the cylinder relative to the head to separate them would involve lessening the distance between the shoulders mentioned, and this the wedge prevents.

As a result of this invention, it will be noted 55

that an improved securing device is provided which may be applied to various types of tools wherein it is desired to lock a plurality of relatively rotatable threadedly connected parts together. It will further be noted that an improved securing device is provided of an extremely simple and rugged design and may be readily applied to a tool of standard construction with a minimum of change, it being necessary only to provide a slot in one part and a groove in the other so that the locking wedge may be driven in the slot and groove. It will still further be evident that by the provision of the slot in one part and the annular groove in the other, the wedge may be driven into position without positioning the relatively rotatable parts in a predetermined manner, and as a result, the joint 12 between the parts when worn may be tightened simply by releasing the wedge, turning the parts relative to each other, and then again driving the wedge in position. These and other advantages of the improved securing device will be clearly apparent to those skilled in the art.

While there is in this application specifically described one form which the invention may assume in practice, it will be understood that this form of the invention is shown for purposes of illustration and that the invention may be modified and embodied in various other forms without departing from its spirit or the scope of the appended claims.

What I claim as new and desire to secure by Letters Patent is:

1. A securing device for locking the threaded joint between a pair of relatively rotatable parts against loosening comprising means forming a slot in one part, means forming an annular groove in the other part, and a wedge driven in the space formed by said slot and groove and acting to effect relative movement of said parts in a direction axially of said threaded joint, to bind the threads.

2. A securing device for locking the threaded joint between a pair of relatively rotatable parts against loosening, irrespective of their position of relative rotation, comprising portions forming a recess on one of said parts and portions forming a recess on the other of said parts, said recesses cooperating irrespective of the position of relative rotation between said parts to form a transverse wedge-receiving opening, and a wedge driven in said opening and engaging said parts and acting longitudinally of the axis of said parts to move said parts in a direction to bind the threads.

3. A securing device for locking the threaded joint between a pair of relatively rotatable parts against loosening, irrespective of their positions of relative rotation, comprising portions, in part on one of said parts and in part on the other thereof, cooperating in all positions of relative rotation of said parts to form a transverse opening, and a securing element arranged in said opening and having portions cooperating respectively with said different parts to lock said parts together with a wedging action, said securing element upon adjustment thereof exerting its wedging action substantially wholly in a direction to move said parts oppositely longitudinally of the axis of the joint to bind the threads.

4. In combination, a pair of threadedly connected members respectively carrying oppositely facing surfaces which face longitudinally of said

members and approach each other on relative rotation between said members in the direction to effect disconnection thereof, and means adjustable, irrespective of the angular position of the threadedly connected members relative to each other, to engage said surfaces to preclude approach thereof.

5. The combination with a member having a bore and a relatively rotatable member having a cylindrical portion extending within said bore, of a device for locking said members together including means forming a slot internally in said first mentioned member and at one side thereof and means forming an annular groove on the outer periphery of said second mentioned member, said slot and groove cooperating to form a transverse opening between said members having relatively inclined surfaces facing oppositely with respect to each other and each facing generally longitudinally of said members, and a wedge driven in said opening and engaging said members for locking the members together with a wedging action.

6. In combination, a pair of members threadedly connectible by relative rotation upon a common axis, and means for preventing undesired separation of said members including a wedge extending in lines tangential to a cylinder of substantial diameter struck from said common axis and means on said members providing oppositely facing surfaces each facing generally longitudinally of said common axis, one on one of said members and the other on the other of said members and both engaged by said wedge and pressed apart by the latter, and cut by a plane which includes said axis and is perpendicular to said tangential lines.

7. In combination, a member having a threaded bore, a member having a threaded portion receivable in said bore and adapted to have its threads engage the threads of said bore, an annular groove in the periphery of said second member, said first mentioned member having a recess therein providing an inclined wedging surface facing generally longitudinally thereof but at an angle to a plane to which the axis of the threaded bore of said member is perpendicular, said recess lying substantially in the same general transverse planes with said groove, when said threaded parts are in desired engaged relation, and a wedge receivable in part in said recess and in part in said groove and cooperating with the said inclined wedging surface and with a generally oppositely facing edge of said groove to hold said parts in engaged relation.

8. In combination, a member having a bore therein and a recess communicating with said bore and providing an inclined wedging surface facing generally longitudinally of said member and at an angle to a plane to which the axis of said bore is perpendicular, a member having a portion receivable in said bore and having a peripheral groove, said members having threaded portions cooperating to connect said members and said groove and recess lying substantially in the same planes transverse to the axis of said bore when said members are in desired coupled relation, and a wedge receivable in part in said recess and in part in said groove and cooperating with said inclined wedging surface and with a generally oppositely facing edge of the groove to prevent unscrewing of the aforesaid threaded portions.

FRANK E. SINCLAIR.
